UNITED STATES PATENT OFFICE

167,857

OXYGEN MASK

Allan M. Russell, Shaker Heights, Ohio

Application April 28, 1951, Serial No. 14,998

Term of patent 14 years

(Cl. D83—1)

To all whom it may concern:

Be it known that I, Allan M. Russell, a citizen of the United States, and resident of Shaker Heights in the county of Cuyahoga, State of Ohio, have invented a new, original, and ornamental Design for an Oxygen Mask, of which the following is a specification, reference being had to the accompanying drawings, forming a part thereof.

Fig. 1 is a front elevational view of an oxygen mask showing my new design;

Fig. 2 is a side elevational view thereof; and

Fig. 3 is a sectional view thereof taken on line 3—3 of Fig. 1.

I claim:

The ornamental design for an oxygen mask, as shown.

ALLAN M. RUSSELL.
